UNITED STATES PATENT OFFICE.

PIERRE J. CHÉRON, OF NEW YORK, N. Y., ASSIGNOR TO TOWLE MANUFACTURING COMPANY, OF NEWBURYPORT, MASSACHUSETTS, A CORPORATION OF MASSACHUSETTS.

DESIGN FOR A HANDLE FOR SPOONS OR ANALOGOUS ARTICLES.

48,884.

Specification for Design.

Patented Apr. 18, 1916.

Application filed November 22, 1915. Serial No. 62,929. Term of patent 7 years.

To all whom it may concern:

Be it known that I, PIERRE J. CHÉRON, a citizen of the United States, residing at New York city, in the county of New York and State of New York, have invented a new, original, and ornamental Design for a Handle for Spoons or Analogous Articles, of which the following is a specification, reference being had to the accompanying drawing, forming a part thereof.

In the accompanying drawing, Figure 1

is a representation of the front of a spoon showing the new design, Fig. 2 is a representation of the back of a spoon showing the new design, and Fig. 3 is a cross-section of the handle shown in Figs. 1 and 2, taken at the dot and dash line on Fig. 1.

I claim:

The ornamental design for a handle for spoons or analogous articles substantially as shown, or any colorable imitation thereof.

PIERRE J. CHÉRON.
